(57) **CLAIM**

The ornamental design for a jewelry, as shown and described.

DESCRIPTION

FIG. 1 is a front, right and top perspective view of a jewelry wing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a front perspective view showing the jewelry and the ring setting in a separated state; and,

FIG. 10 is a rear perspective view showing the jewelry and the ring setting in a separated state.

The broken lines in the figures illustrate portions of the jewelry that form no part of the claimed design.

1 Claim, 10 Drawing Sheets
